UNITED STATES PATENT OFFICE.

LYMAN MIDDLEDITCH, OF NEW YORK, N. Y.

SHEET-REGISTERING MECHANISM.

1,252,604.

Specification of Letters Patent.

Patented Jan. 8, 1918.

Application filed July 6, 1914. Serial No. 849,284.

To all whom it may concern:

Be it known that I, LYMAN MIDDLEDITCH, a citizen of the United States, and a resident of New York city, in the county of New York and State of New York, have invented certain new and useful Improvements in Sheet-Registering Mechanism, of which the following is a specification.

The present invention has reference to 10 registering devices and has for its main object simple and effective means for positively moving the sheet into register with a guide and for maintaining it in register after the registering members have ceased 15 to act upon the same.

The invention consists more particularly in an upper and a lower registering member which engage the sheet on opposite sides thereof and frictionally carry it into register with the guide. In the preferred embodiment here shown the lower registering member is slidably mounted while the upper registering member moves in a curvilinear path. These members move with the same 25 surface speed when engaging the sheet so as to prevent buckling or improper movement of the sheet during the register. In connection with the above there is also employed a top guide which engages the sheet at a point 30 outside the plane in which the lower slide- 35 able registering member is located. This top guide preferably engages the sheet in advance of the time that the registering members take hold of the sheet and stays in contact therewith until after the registering members have ceased to act upon the sheet. The result of this construction is that after 40 the registering members have ceased to move the sheet forward the top guide will prevent the sheet from springing back from the side guide, as it would do if the paper had become buckled during the registering action.

Other features of construction, combination of parts and arrangement of elements 45 will appear as the specification proceeds.

In the accompanying drawings the invention is embodied in a concrete and preferred form but changes of construction may be made without departing from the spirit 50 and scope of the invention as expressed in the appended claims.

In the said drawings:

Figure 1 is a side elevation of a registering mechanism embodying the invention.

Fig. 2 is a plan view thereof.

Fig. 3 is a transverse sectional view on the line 3—3 of Fig. 1.

Fig. 4 is a longitudinal sectional view on the line 4—4 of Fig. 3, certain parts being omitted for the sake of clearness. 60

Fig. 5 is a horizontal section substantially on the line 5—5 of Fig. 4.

Figs. 6 and 7 are views substantially like Fig. 4 and illustrating different stages of the operation from that shown in Fig. 4. 65

Similar characters of reference indicate corresponding parts in the different views.

1 indicates the bed of the machine provided with a groove 2 in which the framing 3 of the registering mechanism is adjustably mounted, the said bed being provided with a number of holes 4 into which the bolts 5 may be secured after moving the frame 3 to the desired position. 70

6 is a shaft forming a part of the feeding machine provided with a bevel gear 7 keyed to the shaft 6 and adjustable lengthwise thereof in a well-known manner. The framing 3 of the registering mechanism carries a rotatable shaft 8 provided with bevel gears 80 9 at its opposite ends, thereby making the device reversible so that motion may be imparted by the said shaft 8 by either gear 9 meshing with the gear 7, the latter being reversed to correspond with the position of 85 carriage 3. Loosely mounted on the shaft 8, or in a bushing thereof, are two supporting arms 10 which carry on their outer ends a shaft 11. Motion is imparted to the gear 13 loose on shaft 11 by means of the gear 12 90 fast on the shaft 8. The gear 13 also carries a cam 13^a which by engaging with the bearer 14 suitably mounted on a stud 15, causes the shaft 11 to be raised and lowered by the rotation of the parts. The gear 13 further 95 carries the upper registering member 16 which, when the arms 10 are lowered and the gear 13 is rotated at definite periods, engages the sheet on the upper sides thereof. A spring 17 urges the cam 13^a into engagement with the bearer 14 and provides sufficient tension to exert a pull on the sheet. 100

Mounted in the sheet support 18 is a 105 slide-able lower registering member 19, said lower and upper registering members being in the same vertical plane so that the paper will be gripped between the two. The said lower registering member 19 is provided with a rack 20 which is actuated by a sector 21 mounted on the center 15 and adapted to re- 110

ceive an oscillating motion. In order to impart a uniform surface speed to the said lower member 19, the sector 21 is preferably moved in one direction by gear means, shown here as two teeth 22 and 23, one of which is carried by the rotating shaft 8 and the other of which is connected to the sector 21. The said sector 21 is further provided with a cam extension 24 adapted to be engaged by the restoring member 25 moving with the gear 13. 10 26 is a top guide pivotally supported on the center 27 and connected by means of a rod 28 and pin and slot connection 29 to an extension 30 forming a part of the arms 10. 15 A spring 31 is provided whereby when the top guide is in its lowermost position the paper will be held under slight tension. Said top guide, of which there are shown two in this instance, engages the paper at 20 a point outside the vertical plane of the lower slidably mounted registering member 19. 32 is the guide, in this instance a side guide, against which the sheet is registered. After the sheet is fed into position between the upper and lower registering members 16 and 19, the operation of the parts is so timed that the top guide 26 descends and holds the sheet with a slight tension against the sheet support 18. The arms 10 are now 30 lowered, the member 16 meanwhile rotating, and the said member 16 clamps the sheet against the lower member 19. The parts are now substantially in the position shown in Fig. 4 and the upper and lower registering members now move simultaneously at a uniform speed, thus drawing the sheet sidewise into engagement with the side guide 32, the sheet being prevented from buckling or from otherwise becoming displaced by the top 35 guide 26. When the sheet has been brought into register the arms 10 ascend and the lower member 19 has reached the limit of its motion in one direction, the top guide 26, however, remaining in contact with the sheet, 40 as shown in Fig. 6. The top guide 26 now rises out of engagement with the sheet and the continued rotation of the gear 13 now brings the restoring member 25 over against the cam extension 24 of the sector 21 and 45 moves it back into its original position, thereby advancing the lower member 19 ready to receive a new sheet. This stage of the operation is shown in Fig. 7.

It is of course understood that after the sheet has been side registered it will be moved away in the usual manner and brought down to the printing or other machine to which it may be contemplated to send it.

What is claimed, is:

60 1. Sheet registering mechanism comprising: a guide, two registering members frictionally engaging the sheet on opposite sides to register it against the guide, a movable top guide adjacent to the first guide and under which the sheet is drawn to prevent

buckling, and means for causing said top guide to engage the sheet substantially not later than the registering members move the sheet and to remain in contact therewith until after the registering members release the 70 sheet.

2. Sheet registering mechanism comprising: a guide, two registering members for frictionally engaging the sheet on opposite sides to register it against the guide, means 75 for imparting a uniform surface speed to said registering members, a top guide adjacent to the first guide under which the sheet is drawn to prevent buckling, and means for causing said top guide to engage the sheet substantially not later than the registering members move the sheet and to remain in contact therewith until after the registering members release the sheet. 80

3. Sheet registering mechanism comprising: a guide, two registering members acting on opposite sides of the sheet to register it against the guide, one an upper member having a curvilinear motion, the other a lower member having a rectilinear motion, 85 means for actuating said members, a top guide adjacent to the first guide under which the sheet is drawn to prevent buckling, and means for causing said top guide to engage the sheet substantially not later than the registering members move the sheet and to remain in contact therewith until after the sheet is released by the registering members. 90

4. Sheet registering mechanism comprising: a guide, two registering members acting on opposite sides of the sheet to register it against the guide, one an upper member having a curvilinear motion, the other a lower member having a rectilinear motion, 105 means for imparting a uniform surface speed to said members, a top guide adjacent to the first guide under which the sheet is drawn to prevent buckling, and means for causing said top guide to engage the sheet substantially not later than the registering members move the sheet and to remain in contact therewith until after the sheet is released by the registering members. 110

5. Sheet registering mechanism comprising: a rotatable shaft, another rotatable member, supporting means for the second shaft pivotally mounted on the first shaft, means for imparting rotation to the second member from the first shaft, means for lifting and lowering the second member, an upper registering member carried by the said second member, a slidably mounted lower registering member, an oscillating member for effecting the reciprocation of 120 said slidably member, means carried by the first shaft for moving said oscillating member in one direction, and means carried by the second member for moving said oscillating member in the other direction. 125 130

6. In a registering device, a lower registering member slidably mounted, a rack carried thereby, a sector mounted to oscillate and adapted to engage with said rack, a rotating member for moving said oscillating member in one direction, another rotating member for moving it in the opposite direction, an upper registering member, and means for causing said upper registering member to operatively engage the sheet.
7. In a registering mechanism, a lower registering member slidably mounted, a rack carried thereby, an oscillating sector adapted to engage said rack, a rotating member, gear means between said rotating member and said sector for moving it in one direction, and cam mechanism for moving said sector in the other direction.
8. In a registering mechanism, a lower registering member slidably mounted, a rack carried thereby, an oscillating sector adapted to engage said rack, a rotating member, gear means between said rotating member and said sector for moving it in one direction, another rotating member, cam

means between said second rotating member and said oscillating member for moving it in the opposite direction, and an upper registering member mounted on said second rotating member.

30

9. Sheet registering mechanism comprising: a sheet support, a guide against which the sheet is to be registered, a lower slidable registering member mounted in said sheet support, means for reciprocating said member, an upper registering member adapted to engage the sheet above the reciprocating member in the sheet support, means for actuating said upper registering member, and a top guide adapted to engage said sheet at a point outside the plane of the lower slideable member.

35

Signed at New York city in the county of New York and State of New York, this 2nd day of July A. D. 1914.
